UNITED STATES PATENT OFFICE

2,366,555

HIGH-FREQUENCY APPARATUS

Simon Ramo, Schenectady, N. Y., assignor to
General Electric Company, a corporation of
New York

Application March 1, 1940, Serial No. 321,746

5 Claims. (Cl. 250—27)

The present invention relates to improvements in electronic apparatus for obtaining amplification and other conversion effects at frequencies so high that electron transit time considerations play a controlling part in the operation of the apparatus.

The invention makes use of the so-called "velocity modulation" principles which are described in U. S. Patent No. 2,220,839, granted November 5, 1940, in the name of W. C. Hahn. However, whereas Hahn has employed an elongated beam tube of the cathode ray type for producing the effects desired, it is proposed in the present instance to utilize a more compact structure in which the electron beam is caused to traverse a helical or other complex path. A significant advantage, in addition to compactness, which is realized by this means consists in the possibility of causing a given element of the electron stream to traverse the same modulating or energy-absorbing agency a large number of times so as to produce cumulative effects.

The features desired to be protected herein are pointed out with particularity in the appended claims. The invention itself, together with further objects and advantages thereof, may best be understood by reference to the following description taken in connection with the drawings, in which Fig. 1 represents a longitudinal view in partial section of an apparatus suitably embodying the invention; Figs. 2 and 2—a are fragmentary sectional views illustrating certain details of the construction of Fig. 1; Fig. 3 is a schematic representation showing the manner in which the electrode structure of Fig. 1 may be employed in an amplifying system; Figs. 4, 5, and 6 are diagrammatic representations useful in explaining the invention; Fig. 7 is a sectional view taken on line 7—7 of Fig. 1; Fig. 8 is a cross-sectional view showing an alternative embodiment of the invention; Fig. 8—a is a fragmentary sectional view illustrating a particular detail of Fig. 8; Figs. 9 and 10 are diagrammatic perspective views, taken in different planes, of a further alternative application of the invention; Fig. 11 is a diagrammatic representation useful in explaining the operation of the apparatus of Figs. 9 and 10; Figs. 12 and 13 are partial sectional views taken in different planes of a fourth possible embodiment of the invention; Fig. 14 is a sectional view, taken on line 14—14 of Fig. 12; Fig. 15 is a diagrammatic view showing still another development of the invention and Figs. 15—a and 15—b are fragmentary sectional views illustrating certain details of the construction of Fig. 15.

An important feature of the invention consists in the provision of means for producing a stream of orbitally moving electrons in which the center of orbital motion progresses continuously along a given axis—as is true, for example, when the electron path is of helical character. This condition may be fulfilled in one way by the use of a construction such as is shown in Fig. 1.

The construction referred to includes an evacuated envelope 10 within which there is provided a generally cylindrical metal structure 11. This cylinder is substantially closed at one end by a pair of semi-circular plates 12 and 13 (Fig. 2—a) which are connected by an axially extending wall part 14. It is provided at the other end with a pair of electrically separate collecting electrodes 15 and 16.

For the production of an electron stream there is provided an electron gun comprising a cathode 18 and a pair of accelerating and focusing cylinders 19 and 20. After issuance from the gun, the electrons are caused to move more or less tangentially with reference to the wall of the cylinder 11 by means of a deflecting plate 22 which is adapted to be maintained at a slightly positive or negative potential with respect to the cylinder. Deflection in the other plane, that is, axially of the cylinder, is accomplished by a second deflecting plate 23 which is appropriately biased for that purpose.

After traversing a generally semi-circular path the electrons enter the main space enclosed by the cylinder 11 through an opening 25 provided at the end of the wall part 14 (see Fig. 2). A component of axial motion is imparted to the electrons by the field existing between the deflecting plate 23 and the end wall of the cylinder 11. The more or less linear motion originally imparted to the electron stream by the electron gun is converted into circular or spiral motion by the action of a strong magnetic field established axially of the envelope by means of magnetic coils, such as are indicated at 27. In this way the beam is caused to traverse a helical path as the electrons progress along the tube toward the collecting plates 15 and 16. The electron path is indicated most clearly by the dotted line A which is shown in the diagrammatic representation of Fig. 3.

The various elements of the electron gun and the deflecting plates 22 and 23 may be maintained in the desired potential relationship by being connected to an appropriate voltage source, which is conventionally represented in the draw-

ings as a battery 29. It is advantageous to utilize the cylinder 11 as the ground point of the system.

In order to permit high frequency effects to be obtained through the agency of the helically moving electrons, the cylinder 11 is provided with a pair of rectangular openings 31 and 32 which are spaced both axially and circumferentially with respect to one another. Rectangular electrode elements 34 and 35 are respectively positioned in the openings just referred to, these elements being of such size as to assure the existence of gaps between their edges and the corresponding edges of the openings.

Referring particularly to the electrode 34, it is contemplated that this electrode shall be used as an input element in a manner analogous to an input grid. If it be assumed in this connection that the potential of the electrode is caused to vary at high frequency with respect to the potential level of the cylinder 11, it is apparent that varying potential gradients will be established across the gaps which bound the electrode, including especially the gaps 31 and 32 which extend longitudinally of the cylinder. Moreover, the gradients thus produced will obviously tend to affect in some degree the velocity of the electrons which successively traverse the gaps in their passage around the circumference of the cylinder 11. It has been pointed out in the aforementioned Patent No. 2,220,839 of W. C. Hahn that cumulative modulation effects may be obtained with a two-gap electrode system provided a proper relationship exists between the dimensions of the electrode, the velocity of the electron stream and the desired operating frequency of the system. More specifically, with reference to an arrangement such as that shown in Fig. 1, such cumulative effects may be obtained provided the transit time of a given electron passing across the face of the electrode 34 between the gaps 31 and 32 is equal to a half-cycle of the operating frequency or to some odd multiple thereof. Under these circumstances it is found that an electron which is accelerated as it passes the first gap 31 will be again accelerated as it traverses the second gap 32. Similarly, an electron which starts out at such a point in the cycle of potential variation of the electrode 34 as to be decelerated at the gap 31 will be further decelerated upon its traversal of the gap 32. This mode of operation not only provides an extremely effective mechanism for producing velocity variations in the electron stream, but also avoids certain input losses which are regarded as inevitable where high frequency effects are sought to be obtained with the conventional type of input grid.

In the previously cited Hahn application the principles referred to in the foregoing have been fully explained with reference to a system in which the electron stream is caused to traverse a linear path. It appears, however, that these principles are equally applicable in connection with a system such as that now under consideration and, in fact, that their application to such a system presents certain important advantages. In particular, it is to be noted that with the construction of Fig. 1, the various electrons may be caused to traverse the modulating gaps 31 and 32, a plurality of times (see Fig. 3), so that, with proper phase adjustments, the effectiveness of the input system may be multiplied without complication of structure.

In an arrangement such as that shown wherein the helical path of the electrons is controlled by means of a uniform magnetic field, little difficulty

is experienced in assuring a desired correlation between the orbital transit time of the electrons and the rate of potential variation of the input electrode. This is due to the fact, demonstrable mathematically, that the time required for the various electrons to complete a single orbital turn is controlled exclusively by the strength of the magnetic field. Consequently, for a given field strength, irrespective of the velocity with which a given electron may leave the electrode 34 after an initial traversal of the gaps 31 and 32, it will return to the vicinity of the electrode within a fixed and invariable time. Therefore, if the strength of the magnetic field is properly adjusted to cause the time of orbital transit of each electron to correspond to some whole number of cycles of the operating frequency, the effect of the input system upon such electron will be additive for each of its successive traversals of the electrode 34. The diameter of the electron orbit may be controlled and made commensurate with the dimensions of the cylinder 11 by appropriate regulation of the velocity with which the electrons are projected from the electron source.

The matters referred to in the preceding paragraph may be more clearly understood by referring to Fig. 4. In this figure the solid line B may be taken to represent the assumed path of an electron whose velocity corresponds to the average or unmodulated velocity of the electron stream. The point 0 is considered to represent a region in which the stream is subjected to a high frequency modulating potential. An electron which passes the modulating agency in such time phase as to be accelerated thereby, may be expected to follow a path of somewhat greater radius than the path B, such enlarged path being represented, for example, by the dotted line C. On the other hand, decelerated electrons will describe a smaller orbit as indicated by the dotted line D. Theoretical analysis shows, however, that each electron will require precisely the same time to traverse its orbit and return to the point 0. Moreover, it is found that each electron will pass through the point 0 along a line substantially coincident with that of its initial transit.

Fig. 5 shows the way in which the considerations discussed above are affected by the presence of a component of axial velocity in the electron stream motion. Thus, in this figure, the solid line E represents the path of a helically moving electron of average velocity, while the dotted lines F and G respectively show the lines followed by electrons which are respectively accelerated and decelerated by the effect of modulating potentials applied as the various electrons traverse the region occupied by the line 0'. It will be noted that for the case of repetitive acceleration the electron orbit increases progressively, while for the case of repetitive deceleration a progressive decrease in electron orbit occurs. However, the trajectory of each electron causes it to pass repeatedly through the line 0'.

In order to understand the possibility of obtaining amplification effects as a result of the phenomena discussed in the foregoing, it will be helpful to refer to the action of a circularly moving electron stream which is caused to traverse a modulating gap subjected to cyclically varying potential gradients. This situation is illustrated diagrammatically in Fig. 6, which may be taken to show the conditions occurring at various points around the orbit of an electron stream which is caused to traverse a modulating gap at 0''. For the case illustrated, it is assumed that the fre-

quency of potential variation across the gap is such that eight complete cycles of variation occur during the time required for a single electron to traverse its orbit. The solid dots *a* may be taken to represent individual electrons, and, considered in the aggregate, they show the condition of the beam at a particular instant of time.

As the various electrons move azimuthally, those whose velocity exceeds the average beam velocity seek an orbit of greater radius, while the decelerated electrons seek an orbit of reduced radius. As a consequence of this action, observations taken between various closely spaced azimuthal planes will show that the electron density measured at most points around the electron path varies materially with time. This variation is mainly a function of the relative displacement of the centers of gyration of the various electrons and is found to be greatest between planes which are located approximately ninety mechanical degrees from *0*°, such planes being indicated at *b* and *b'*.

It will be noted that at the instant which is represented in Fig. 6, considerable bunching of the electrons exists between the planes referred to at the upper side of the electron orbit, while a relative paucity of electrons is to be noted between the same planes at the other side of the orbit. On the other hand, this situation would be found to be reversed at an instant taken a half-cycle later. It is, therefore, apparent that on either side of the electron orbit the portion of the beam between the planes *b* and *b'* will be characterized by a high degree of "charge density modulation," that is, cyclical variation of electron density with time. On the other hand, in a region displaced ninety degrees from that just considered, that is to say, between the planes *c* and *c'*, substantially no variations of the charge density with time will be observed, and it may therefore be said that at this point the charge density modulation of the beam is negligible.

The condition of negligible charge density modulation last referred to will be realized again when the beam returns to its starting point at the region *0*°, and at this point the beam will be characterized by its initial, relatively uniform charge density, although the velocity variations produced by the primary modulating action of the modulating system will still exist in the beam. Upon a further traversal of the gap by the electron stream, these variations will be increased in accordance with the principles previously explained. Therefore, since the charge density modulation occurring between planes *b* and *b'* is a function of the velocity variation which produces it, it is apparent that such charge density modulation will be greater for each successive orbital passage of the electron stream.

As a result of the considerations stated in the foregoing, even a relatively slight velocity modulation produced at the modulating gap *0*° may, by additive action, be made to cause relatively great charge density variations in the region *b*, *b'*. Therefore, if some means are provided by which the charge density variations existing at *b*—*b'* can be utilized in an appropriate manner, the system as a whole may be employed for amplification purposes.

Referring again to the arrangement of Fig. 1 it will be seen that this arrangement is well adapted to make use of the considerations just described. Specifically, the electrode 34 may, by connection to an appropriate input circuit, be caused to produce velocity modulation of the

helically moving electron stream. (It will be understood in this connection that the existence of the two modulating gaps 37 and 38 in no way affects the applicability of the discussion which has been given above). The relatively great axial length of the electrode 34 assures that each electron will pass it a plurality of times, the number of such traversals being determined, of course, by the pitch of the helix which the electron stream describes. The resultant high degree of velocity modulation produced in the stream before it passes beyond the extremity of the electrode may be expected to produce a correspondingly high degree of charge density variation in those azimuthal planes which include the electrode 35 and the gaps 39 and 40 which bound this electrode. Consequently, if the electrode mentioned is connected to an appropriate circuit, an output voltage of useful magnitude may be obtained.

The provision of two gaps at the adjacent edges of the electrode 35 serves a function analogous to the two gaps provided in connection with the input electrode 34. Specifically, if the dimensions of the electrode 35 are properly correlated to the electron transit time, cumulative energy abstraction effects will be produced at the two gaps. This condition is most adequately fulfilled when the dimensions of the electrode 35 correspond to those of the electrode 34. Again, for reasons analogous to those given in connection with the input structure, additional cumulative effects may be obtained by causing the various components of the stream to traverse the various output gaps a large number of times—as by the use of an output electrode which is of relatively great length with respect to the pitch of the helical path of the stream.

A diagrammatic view of the amplifying system which has just been described is provided in Fig. 40 of the drawings. In this figure an input electrode 34, corresponding to the similarly numbered element of Fig. 1, is shown as being connected to an input circuit which includes the parallel combination of an inductance 45 and a condenser 46. Similarly, an output circuit connected with the electrode 35 is shown as comprising an inductance 47 and a capacitance 48. The application of a relatively weak signal to the input circuit would be expected to result in the production of a much stronger signal in the output system as a result of the amplification effects above described.

The construction shown in Fig. 1 incorporates certain practical features which have not so far been described and which include two semi-cylindrical metal parts 50 and 51 (see Fig. 7). These are placed in juxtaposition and are joined at their abutting edges by the provision of outwardly projecting flanges as indicated at 52 and 53. The continuous shielding system thus formed 60 serves to prevent undesired radiation of power from the apparatus and also to prevent objectionable back-coupling between the various electrode elements.

For supplying voltage to the input electrode 34, there is provided on the outer peripheral surface of the shield part 50, a tubular metal member 55, which, in combination with a lead-in conductor 56, forms a concentric transmission line suitable for connecting the electrode 34 to a signal generating or receiving agency. A similar concentric line arrangement is provided in connection with the output electrode 35, the outer member of such system being shown at 58 in Fig. 7 and the inner member at 59.

In addition to the use of the apparatus of Fig.

1 as an amplifier, it may also be employed for detection purposes by appropriate use of the collecting electrodes 15 and 16. (When the apparatus is employed for this purpose, no use is made of the output electrode 35.) In detecting a received signal, the signal is impressed on the electrode 34 in accordance with the procedure previously discussed. As a result of the modulating effect of the electrode, the electrons which are decelerated are caused to traverse an orbit of smaller radius than the normal orbit of the unmodulated portion of the electron stream. This latter factor is used in the production of detection effects in the following manner.

The diameter of the electrode 15 is made sufficiently small so that in the absence of a modulating signal applied to the electrode 34 substantially the entire electron stream impinges on the electrode 16. However, when the beam is modulated by the application of a signal to the input electrode 34, the decelerated electrons are enabled to reach the plate 15 as a result of their reduced orbit. Consequently, an appropriate circuit connected to the plate 15 may be made to develop a D.-C. voltage of varying magnitude depending upon the low frequency variations of the input signal. Such a circuit is shown in the drawing as including a resistor 60 connected in series circuit with the electrode 15 and having a pair of output terminals 61 connected across it.

The invention may be practiced with numerous structures other than that which is illustrated in Fig. 1 and one alternative embodiment is shown in Fig. 8. In this case, the electrode structure is enclosed within an insulating envelope 65 which includes a deeply reentrant portion 66. For the establishment of an electron beam of proper character there is provided an electron gun having as part thereof, a generally annular cathode 68 whose outer peripheral surface is activated to assure electron emission thereof upon heating of the cathode. The annular stream of electrons which is generated by this means is concentrated into a thin sheet by the application of appropriate voltage to a pair of annular concentrating electrodes 69 and 70. Radial acceleration of the beam is further assured by the use of two additional annular electrodes 72 and 73 which are maintained at a relatively high voltage with respect to the cathode. Further, during its passage between the electrodes 72 and 73 the electron stream is given a component of velocity in the axial direction by the maintenance of an appropriate difference of potential between the electrodes 72 and 73, the electrode 73 being maintained at the higher potential for this purpose.

The agencies referred to, taken in connection with a strong magnetic field assumed to be produced axially of the envelope by means not shown in the drawings, cause the electron stream to move toward the end of the envelope remote from the cathode 68 in a hollow continuous sheath which has components both of rotary and of axial motion. As in the arrangement of Fig. 1 the motion of any individual electron in the stream is along a helical path.

For the production of high frequency effects there is provided an electrode system which includes a pair of co-axial cylinders 75 and 76. At the top of each cylinder, in the position illustrated in the drawings, there is provided a rectangular opening, such openings being shown at 78 and 79, as being in aligned relationship. The openings referred to are occupied by rectangular electrodes 80 and 81 which conjointly serve a

function similar to that served by the input electrode 34 of Fig. 1. In this connection the electrodes 80 and 81 are both provided with lead-in conductors as indicated at 83 and 84 and in use, 5 are connected to a common source of high frequency potential (not shown). The action of the electrodes 80 and 81 on the beam is precisely similar to that of the electrode 34 of Fig. 1 and need not be further described. It may be pointed out, however, that the use of two oppositely disposed electrodes tends to produce a somewhat stronger modulating effect than that produced by a single electrode element.

At the extremities of the cylinders 75 and 76 additional rectangular openings are provided which accommodate an output electrode in the form of a U-shaped member having opposed plate-like parts 86 and 87 (see Fig. 8a). The structure thus formed is adapted to serve as an output electrode and to this end is provided with an appropriate lead-in conductor as indicated at 88. As in the arrangement previously described, the production of high frequency modulating effects by the input electrodes 80 and 81 serves to 20 produce amplification effects at the output electrode 86. After its traversal of both the input and output electrodes, the electron beam may be collected on the end wall 90 which joins the cylinders 75 and 76.

A still further possible modification of structure is that shown in Figs. 9 and 10 wherein only the high frequency electrode system is illustrated. The view which is represented in Fig. 10 will be recognized as being taken in a plane ninety 35 degrees displaced from that of Fig. 9. In both figures, the enclosing envelope is omitted for the sake of clarity.

The construction which is illustrated in the figures just referred to comprises a uni-potential 40 part having a generally cylindrical center portion 95 and a pair of quadrangularly displaced end-portions 96 and 97. All these portions are of hollow configuration. The end portion 96 is arranged in face-to-face relation with an independent semi-cylindrical part 99, which is also of hollow character and which is adapted to serve as an input electrode. Similarly, the end portion 97 is associated with a hollow semi-cylindrical part 100 which is adapted to serve as an output electrode. In the use of the electrode structure just described, a helically moving electron stream (produced, for example, by the effect of a magnetic field) is caused to traverse the interior of the structure, as indicated by the dotted line H. Voltage is then applied between the semi-cylindrical part 99 and the cooperating part 96 55 by means of an input circuit which is illustrated as including the parallel combination of an inductance 103 and a condenser 104.

60 In accordance with the principles previously described, the various elements of the electron stream which traverse the gaps 106, 107 existing between adjacent edges of the parts 99 and 96 will be variously affected in velocity depending on the potential relationship which exists between the parts at the instant of such traversal. Thus, certain electrons which traverse the gap 65 106 will be accelerated, while other electrons which traverse this gap will be decelerated. Additional velocity variations of generally similar character will be produced at the gap 107.

For present purposes it is desired that successive modulating impulses produced in the manner specified in the last paragraph shall have cumulative effects with respect to the production of

charge density variations at particular points along the electron path. It has already been pointed out in the discussion of Fig. 6 that the occurrence of such variations in a system of the type under consideration depends upon relative displacement of the centers of gyration of the various electrons. For this reason, most effective operation of the particular apparatus shown in Figs. 9 and 10 will obtain when the velocity changes to which any given electron is subjected at the two gaps 106 and 107 are subtractive in nature. That is to say, it is desired that an electron which is subjected to an accelerating influence at the gap 106 shall be subjected to a decelerating influence at the gap 107. When this condition is realized, the path of an initially accelerated electron may be as indicated by the dotted line J of Fig. 11 in which the solid line I represents the normal trajectory of an electron of average intensity. On the other hand, an electron which is subjected to deceleration upon its first traversal of a modulating space will be caused to move as indicated by the dotted line K. This representation, which assumes that each electron is oppositely affected as it passes two diametrically spaced modulating gaps, demonstrates the possibility of obtaining a wide and rapid displacement of the electron orbits by the means specified.

As previously stated, such displacement results in the occurrence of charge density modulation in parts of the beam which are displaced from the velocity-affecting gaps. The charge density modulation thus provided may be utilized in the production of amplification effects by appropriate utilization of the electrode 100 in connection with an output circuit, such as that formed by the tuned combination of a condenser 110 and an inductance 111. It will be noted that the electrode 100 is so positioned with respect to the other parts of the system as to provide a pair of gaps which are quadrangularly displaced from the gaps 106, 107. (Only one of said gaps, indicated at 113, is apparent in the drawings.) For reasons which have been previously given, the charge density variations occurring in the beam are greatest in the vicinity of these gaps so that the effect of the beam on the output system is a maximum for the arrangement illustrated. Consequently—in view of favorable differences in magnitude between the charge density variations and the velocity variations which produce them—a relatively weak input signal applied to the electrode 99 may be expected to produce an amplified output signal across the terminals of the circuit 110, 111.

The modification shown in Figs. 12, 13 and 14 of the drawings represents a combination of the principles employed in the construction of Fig. 1 with those which are utilized in the arrangement of Figs. 9 and 10. In this case, an electron beam generated by an emitting source 115 is caused to traverse a hollow cylinder 116 which it enters through a small opening 119 provided in one of the bounding surfaces (118) of the cylindrical enclosure. A deflecting electrode 121 positioned in the vicinity of the opening 119 serves to impart a component of axial velocity to the beam. This factor, taken in connection with the influence of a strong axial magnetic field produced by some appropriate means (not shown), serves to constrain the beam to a helical path.

The cylinder 116 is provided at each end with a pair of opposed rectangular slots as indicated at

123, 124, 125 and 126. The separate pairs of slots are quadrangularly displaced and are substantially filled by conforming electrode elements numbered 127 to 130 respectively. The oppositely disposed electrode parts are maintained at a common potential by the provision of U-shaped connecting parts indicated at 132 and 133.

The transverse dimensions of the electrodes 127 to 130 are made such that the electron transit time across them corresponds approximately to a half-cycle of the intended frequency of operation of the apparatus or, for extremely high frequencies, to an odd multiple thereof. Furthermore, the total circumference of the cylinder 116 should be such that the time required for a given electron to pass from a selected point, say, the electrode 127, to a diametrically opposite point (that is, the electrode 128) will correspond to a whole number of complete cycles of the operating potential. With these conditions fulfilled, a given electron which is twice accelerated as it successively traverses the gaps which bound the electrode part 127 will be twice decelerated as it traverses the gaps associated with the electrode part 128. The converse will hold for an electron which is initially decelerated. As a consequence of these circumstances, there will be a strong tendency for relative displacement of the centers of gyration of the various electrons to occur. As has already been explained, this provides a mechanism by which amplification effects may be obtained.

As in the arrangements previously described, the electron beam, after its modulation by the electrode parts 127 and 128, is caused to pass into the proximity of the quadrangularly displaced electrode parts 129 and 130. In view of the relatively great charge density variations occurring in the modulated beam as it traverses the planes which include these electrodes, strong excitation of the output system associated with such electrodes may be obtained.

In the use of the system for amplification purposes, input voltage may be applied between the cylinder 116 and the conductive part 132 which connects the electrodes 127 and 128 to produce modulation of the electron beam. An appropriate circuit for this use may include the parallel combination of a condenser 135 and an inductance 136. A tuned output system is illustrated as including an inductance 137 and a condenser 138.

A still further development of which the invention has been found capable is illustrated in Fig. 15, the structure shown therein being the separate invention of John P. Blewett and is claimed in copending patent application Serial No. 385,437, filed March 27, 1941.

In this case there is shown an evacuated envelope 140 (indicated in dotted outline) which encloses a linear cathode 141 of generally filamentary character. (The active portion of the cathode is assumed to consist of the region between the points e and f.) Surrounding the cathode and extending generally coaxially therewith there is provided a high frequency electrode system including a series of cylindrical parts 142 to 146 whose functioning is described in detail in the following.

The cylinder 142, which subtends a major portion of the cathode 141, is maintained at a positive potential with respect to the filament so as to produce radial motion of the electrons emitted in its vicinity. This motion is converted into orbital motion by means of a strong magnetic field established in a direction parallel to the

cathode, as indicated by the heavy arrow M. Also a unidirectional potential is impressed between the electrode 142 and the electrode 143 to cause the electrons to move axially along the electrode system in the direction of the higher numbered electrodes. If desired, further unidirectional potentials may be applied to the other electrodes of the system (namely, the electrodes 144, 145 and 146) to increase this axial motion, but satisfactory operation of the apparatus will obtain if all these parts are at a common potential with the electrode 143. A direct current source such as a battery 149 may be employed for maintaining the potential relationships referred to.

As appears more clearly in Fig. 15-a, the electrode 143 consists of a split cylinder having two semi-cylindrical conducting parts, 143a and 143b, which are insulatingly spaced, and which define a generally cylindrical chamber between them. In the use of the apparatus, these parts are subjected to an alternating difference of potential by means of an appropriate input circuit which is illustrated diagrammatically as including simply a pair of parallel conductors 151 and 152. These conductors are assumed to constitute a standing wave transmission line (e. g. a quarter wave line) which may be excited in any desired fashion. A common battery connection 153 for the two conductors is provided for the purpose of maintaining the average potential of the electrode parts 143a and 143b at a desired value.

By the input arrangement specified, cyclically variable voltages are developed across the gaps which separate the electrode parts 143a and 143b. Consequently, if the circumferential dimensions of the parts are properly correlated to the orbital velocity of the electrons and to the operating frequency of the system, cumulative modulation effects may be obtained as the various electrons successively and repetitively traverse the said interelectrode gaps.

Amplification is obtained with the apparatus described above by making the electrode 145 also of a split cylinder construction, as shown in Fig. 15-b and by connecting the parts 145a and 145b to an appropriate output circuit which is represented diagrammatically as including a pair of parallel conductors 154 and 155. As the various components of the previously modulated beam successively traverse the gaps existing between the electrode parts 145a and 145b, excitation of these parts will be produced, and an output voltage of significant magnitude will be developed across the terminals of the output circuit. After its passage through the electrode 145 the electron stream may be collected by means of an appropriately positioned anode 156.

It is desirable with the construction above described to prevent radially moving electrons from reaching the surface of the envelope 140 and thus producing objectionable wall-charging. To this end the electrodes 142, 144 and 146 are provided with flanged extensions which overlap the interelectrode gaps and prevent egress of electrons by this means. Functionally similar flanges 158 are provided in connection with the gaps which exist between the respective parts of the electrodes 143 and 145.

It will be noted that in the construction of Fig. 15 the input and output gaps are in a common plane rather than being 90 degrees displaced as in the cases previously described. The possibility of this arrangement, which has been found satisfactory for a particular condition of operation, is explained in part by the greater effect of space

charge in a system in which the electron source comprises a central filament as just described. In this situation, the theoretical considerations which indicate a quadrangular displacement of the input and output gaps for cases of relatively low electron density no longer apply with complete accuracy, and a determination of the best relationship between the location of the input gaps and the location of the output gaps may best be made by experimental methods. Even in the arrangements previously referred to, wherein the electron source comprises an electron gun or the like, an experimental adjustment of the gap relationships should be made provided the current density employed is so high as to make space charge a significant factor.

It should also be pointed out in connection with the apparatus of Fig. 15 that the arrangement shown does not necessarily permit all the emitted electrons to follow orbits of uniform radius. It appears, however, that the net effect is to establish a rotating and axially progressing space charge which produces high frequency effects generally indistinguishable from those caused by an electron stream whose form is more definitely fixed.

In the foregoing the invention has been described by reference to particular embodiments. It will be understood, however, that numerous modifications may be made by those skilled in the art without departing from the invention. I, therefore, aim in the appended claims to cover all such equivalent variations as come within the true spirit and scope of the foregoing disclosure.

What I claim as new and desire to secure by Letters Patent of the United States is:

1. High frequency apparatus, including means for producing a stream of orbitally moving electrons in which the center of orbital motion progresses along a given axis, a pair of concentric conducting cylinders arranged one within the other and defining between them an annular space to be traversed by the said electron stream, the said cylinders being respectively provided with elongated gaps contiguous with a common region of the said annular space, said gaps extending parallel to the said axis of progression of the electron stream, common means for producing cyclically varying potential gradients across the said gaps so as to vary the orbital velocity of the electrons which successively traverse the said region, and energy-absorbing means positioned to be affected by variations existing in the electron stream at a point which is axially displaced from the said region.

2. High frequency apparatus including means for producing a stream of orbitally moving electrons in which the center of orbital motion progresses along a given axis, a generally cylindrical conducting structure defining a hollow chamber to be traversed by the electron stream, said structure having a pair of elongated openings therein which extend axially of the member at diametrically opposed regions thereof, elongated conductive elements positioned in said openings but incompletely filling the same so as to provide elongated gaps between the boundaries of the openings and the edges of the elements, means for impressing a high frequency voltage between the elements and the said cylindrical structure thereby to produce variations in the orbital velocity of the various electrons as they successively traverse the said gaps, and energy abstracting means positioned to be affected by variations existing in

the electron stream at a region which is axially displaced from the said gaps.

3. High frequency apparatus including means for producing a stream of orbitally moving electrons in which the center of orbital motion progresses along a given axis, spaced conducting parts defining an elongated gap which extends generally parallel to said axis in proximity to the electron stream, means for impressing a high frequency voltage between the said conducting members thereby to produce variations in the orbital velocity of the various electrons as a result of the potential gradients developed across the said gap, additional conducting parts defining a second elongated gap extending generally parallel to the first gap in a region which is axially displaced therefrom sufficiently to permit the velocity variations of the beam to be effectively converted into charge density variations in the intervening space, said second gap being azimuthally displaced from the first gap by a substantial angle less than 180 degrees at which said charge density variations are maximum, and means connected with the said additional conducting parts and adapted to be excited thereby in accordance with variations existing in the electron stream upon its traversal of the said second gap.

4. High frequency apparatus including means for producing a stream of orbitally moving electrons in which the center of orbital motion progresses along a given axis, means defining an elongated gap which extends generally parallel to said axis in proximity to the electron stream, means for producing cyclically reversible potential gradients across the said gap, thereby to pro-

duce variations in the orbital velocity of the various electrons as they pass the said gap, means defining a second elongated gap extending generally parallel to the first gap in a region which is axially displaced therefrom by an amount sufficient to permit said velocity variations to be effectively converted into charge density variations in the intervening space, said second gap being also azimuthally displaced from the first gap by an angle on the order of ninety degrees so that it coincides with a region of maximum charge density variation, and energy-abstracting means arranged to be affected by the variations existing in the electron stream as it passes the said second gap.

5. High frequency apparatus including means for producing a stream of orbitally moving electrons in which the center of orbital movement progresses along a given axis, a pair of semi-cylindrical conductive parts which are cooperatively positioned to provide axially extending gaps between their juxtaposed edges in proximity to the electron stream, means for producing cyclically reversible potential gradients across the said gaps so as to vary the orbital velocity of the various electrons passing the gaps, a second pair of semi-cylindrical conductive parts which are also cooperatively positioned to provide axially extending gaps between their juxtaposed edges, said last-named gaps being in proximity to the path of the electron stream and being both axially and azimuthally displaced from the first-named gaps, and energy-abstracting means arranged to be affected by the variations existing in the electron stream as it passes the said last-named gaps.

SIMON RAMO.
